(57) **CLAIM**

What is claimed is the ornamental design for a case for a mobile communications device, as shown and described.

DESCRIPTION

FIG. 1 is a rear, bottom, right perspective view of a case for a mobile communications device showing my new design;

FIG. 2 is a front view of the case of FIG. 1;

FIG. 3 is a rear view of the case of FIG. 1;

FIG. 4 is a left side view of the case of FIG. 1;

FIG. 5 is a right side view of the case of FIG. 1;

FIG. 6 is a top view of the case of FIG. 1;

FIG. 7 is a bottom view of the case of FIG. 1;

FIG. 8 is a front, left, bottom perspective view of the case of FIG. 1;

FIG. 9 is a front view of the case of FIG. 1, with cross-sections indicated;

FIG. 10 is a cross-sectional view of the case of FIG. 1 taken in the direction of line 10-10 of FIG. 9;

FIG. 11 is a cross-sectional view of the case of FIG. 1 taken in the direction of line 11-11 of FIG. 9;

FIG. 12 is a cross-sectional view of the case of FIG. 1 taken in the direction of line 12-12 of FIG. 9; and,

FIG. 13 is a cross-sectional view of the case of FIG. 1 taken in the direction of line 13-13 of FIG. 9.

The combination of stippled and linear surface shading in the drawing figures represents a contrast in appearance between the surfaces with a combination of stippling and linear shading and the surfaces with linear shading only.
